CONVERTIBLE COUCH

Philip Cutler, New York, N. Y.

Application January 23, 1935, Serial No. 3,068

1 Claim. (Cl. 5—37)

This invention relates generally to convertible couches wherein an upright back-member is extensible to serve as a companion single bed to the single bed afforded by the surface of the couch. More specifically, the invention relates to a convertible couch wherein the back member is supported on elements of the couch or stationary frame when not in service as a double bed.

10 The main object of the invention resides in the provision of a couch convertible into a double bed by releasing the back member from the stationary frame, opening folding legs mounted at the under surface of the said back member, and allowing the said back member to pivot outwardly about the end members of the stationary frame whereby the back member automatically seeks the level of the stationary couch frame.

Another object of the invention is in the provision of structure as just described wherein means are afforded for the complete separation of the back member as a single bed from the bed afforded by the stationary frame.

A further object of the invention is in the provision of structure wherein means are provided for the support of a back member for a couch in a novel form, the said means being for the mattress or upholstery portion of the back member and for the frame or spring portion of the back member.

30 Another object of the invention resides in the provision of a convertible couch which is economical to manufacture, easy to operate, comprised of a minimum number of parts and which is adapted to furnish a most aesthetic looking article of furniture.

These objects and other incidental ends and advantages will hereinafter appear in the progress of this disclosure and as pointed out in the appended claim.

40 Accompanying this specification are drawings showing a preferred embodiment of the invention and wherein the reference characters appearing in the drawings designate corresponding parts throughout the several views thereof.

45 In accordance with the drawings:

Figure 1 is a view in perspective of a preferred embodiment of a convertible couch in accordance with the invention.

50 Figure 2 is a transverse sectional view of Figure 1 along the plane 2—2 thereof.

Figure 3 is a view in perspective of the stationary and movable truck frames of the convertible couch, the movable truck frame being partly broken away and separated from the stationary

frame, one end piece of the stationary frame being shown as partly broken away.

Figure 4 is a front end elevational view of Figure 3 showing the movable truck frame separated from the stationary frame, the both frames being on the same level while the truck or movable frame is shown pivotally mounted on the end piece of the stationary frame; the dot and dash lines indicating the several positions into which the movable truck frame is capable of assuming with relation to the stationary frame.

Figure 5 is a view in elevation of the rear of the movable truck frame shown mounted on the end pieces of the stationary frame, the said view being shortened along the length thereof.

Figure 6 is an enlarged view in perspective showing one of the two channels affixed to the end pieces of the stationary frame, the said channel being adapted to allow pivot elements from the movable truck to move vertically therein and to be supported thereby.

Figure 7 is a fragmentary plan view partly in section showing the mechanism controlling the operation of the folding legs of the movable truck frame.

Figure 8 is a sectional view of an alternate manner of supporting the back member of the convertible couch, the said alternate manner being in relation to the showing of the back member in Figure 2 of the accompanying drawings.

In accordance with the invention and in accordance with a preferred form shown in the accompanying drawings, the structure is comprised of a stationary frame having end members detachably affixed thereto and a movable truck frame which when in upright position serves as a couch back while when in extended position serves as a single bed in companionship with the single bed offered by the stationary frame. The movable truck frame is supported on two channel members mounted on the inner surfaces of the detachable end pieces of the stationary frame, and it is in these channel members that pivots from the movable truck frame are supported and slidable above the lower limit-

ing wall of the said channel members. When the movable truck frame is in upright position, the pivots thereof bear in the bottom walls of the channel members. In order to extend the truck frame from the upright position, the said frame

is released from the upright position, the folding legs forced outwardly from the undersurface and the entire frame permitted to pivot outwardly by virtue of the weight thereof. As the legs of the frame of the truck member touch

the floor, the pivots of the truck frame ride upwardly and vertically in the channel members until the legs of the truck member all touch the floor at once at which time the level of the truck frame is the same as the level of the single bed afforded by the stationary frame, thereby affording a double bed. The single bed of the truck frame is capable of complete separation from the stationary frame by lifting the pivots thereof from the channel members in the end pieces of the stationary frame.

The novelty of the invention resides in the articulation between the stationary frame and the truck frame and the manner of supporting the said truck frame when in upright position, the said manner of supporting the truck frame being equally applicable to the support of the upright or back of an ordinary couch having an upholstered back with a frame work therefor. Moreover, novelty of the invention resides in the other features hereinafter set forth in a specific description of the preferred form of the invention shown in the drawings.

The stationary frame of the convertible couch is provided with two end pieces 10 and 11 to serve as the arm members of the structure and may be upholstered in any known manner. The upper parts of the arm members are designated by numerals 10' and 11' respectively. The stationary frame is made preferably of angle iron and is assembled from uprights or legs 12, 13, 14 and 15, lower end rails 16 and 17, upper end rails 18 and 19, lower longitudinal rails 20 and 21, and upper rear longitudinal rail 23 and upper front longitudinal wire or flexible band 22, the said member 22 being extended from the upper end rails 18 and 19 by means of the ordinary coil contractile springs. The purpose of having member 22 flexible or resilient is to afford a springable forward edge to the couch. The upper end rails of the stationary frame designated by numerals 18 and 19 support a bed spring which is pivotal for the greater part of the width thereof. The bed spring for the pivotal part thereof is provided with a frame member having end rails 24 and 25 superposing end rails 18 and 19 respectively and pivoting with the latter rails at 24' and 25' respectively. Connecting end rails 24 and 25 is a longitudinal rail member offset downwardly and extending forwardly thereof, the said longitudinal rail member being designated by numeral 26, and being adapted to clear member 22 in the raising and lowering thereof. Beyond pivotal points 24' and 25' are sections 55 of end rails 27 and 28 superposing and connected with the end portions of end rails 18 and 19 respectively of the stationary frame. End rails 27 and 28, and end rails 24 and 25 of the pivotal frame member furnish the supports for the usual contractile coil springs 37 which serve to maintain the known wire or band surface for the support of a mattress 47, the said wire or band surface not being shown in the accompanying drawings.

Numerals 29, 30, 31 and 32 represent reinforcing links between the uprights and the upper and lower end rails of the stationary frame of the couch, while 33, 34 and 35, 36 are slots on the outer surfaces of uprights 12 and 13 respectively, each pair of slots being in alignment. Similarly, uprights 14 and 15 are each provided with a pair of aligned slots 33', 34' and 35', 36' respectively on the outer surfaces thereof. Each of the end pieces 10 and 11 of the stationary frame is provided with fingers having upwardly

offset portions extending from the inner surfaces to cooperate with the slots in the aforementioned uprights whereby the stationary frame acts as a suspension from the end pieces. It can easily be seen, however, that the end pieces 10 and 11 may be supported on the uprights of the stationary frame where the said uprights are designed to be supported on the floor. In this event, the fingers projecting from the inner surfaces of the end pieces 10 and 11 would have downwardly projecting offset portions to cooperate with the slots in the uprights. This invention contemplates such a variation although the drawings omit reference thereto.

As shown in the drawings, the stationary frame affords a bedding storage compartment by providing a bottom wall 38 extending from the lower longitudinal rails 20 and 21 and from the lower end rails 16 and 17, a front wall 39 extending from the lower longitudinal rail 20 to below the wire or band member 22 and from uprights 12 and 14, and a rear wall 40 extending from uprights 13 and 15 and from upper and lower longitudinal rails 21 and 23. The end pieces 10 and 11 furnish side walls for the bedding storage compartment. The walls mentioned in this paragraph may be of any suitable material such as cedar wood or any other adaptable substance.

In order to gain access to the said bedding storage compartment, the pivotal frame, bounded by end rails 24 and 25 and front or longitudinal rail member 26 is raised as is shown in Figure 3 of the accompanying drawings.

Numerical 42 represents any upholstery material such as cloth and is preferably stretched between the front edges of end pieces 10 and 11 and is mounted between lower longitudinal rail 20 and above wire or band member 22 to give the couch a finished appearance in this region as seen in Figure 1 of the accompanying drawings. Numerals 43, 44, 45 and 46 represent supports on which the stationary portion of the convertible couch rests against the floor, 45 and 46 being the known casters while 43 and 44 are leg sections. Behind the leg sections 43 and 44 are casters 48 and 49 to enable easy rolling of the couch. It is easily seen that housings may be provided for the casters 45, 46 and 48 and 49 thereby eliminating leg sections 43 and 44 and thus rendering an improved appearance to the structure.

Between end rails 16 and 18 of the stationary frame is affixed a vertical frame member 50 provided with a vertically extended slot through which a pivoted catch arm 51 rides, the said catch arm being pivoted at 54 to the end rail 24 as shown in Figure 3 of the accompanying drawings. The lower edge of arm 51 is provided with a notch 52 near the outer extremity of the said arm which notch is adapted to catch in a cross member 53 in the slot of frame member 50. Thus, the cross member 53 serves as a bearing for the lower edge of arm 51; when the pivotal spring is raised, the same has a limiting and locked position when notch 52 engages the cross member 53. In order to lower the pivotal spring, arm 51 must be manually pulled forward to disengage notch 52 from cross member 53.

The movable truck frame is now to be described. The said truck frame is comprised of an upper frame work having longitudinal rails 55 and 56 and end rails 57 and 58. These parts as in the case of the stationary frame are preferably of angle iron. The outer surface of the forward longitudinal rail 56 is provided with upright 59 intermediate the length thereof and uprights 60

and 60' at the ends of the said rail 56. The uprights 60 and 60' are each provided with plates 61 and 61' extending inwardly and perpendicularly of plates 60 and 60' respectively. The purpose of the upright 59, 60 and 60' is to serve as a lower support for the mattress 96 when the latter is in vertical position, while the purpose of plates 61 and 61' is to prevent lateral displacement of mattress 96 in all positions.

10 Numerals 62, 63, 64 and 64' (the last mentioned not being shown on the drawings) represent reinforcing links or bars between the end rails and the longitudinal rails of the upper frame work of the movable truck frame. The said truck frame 15 is provided with a spring surface suspended or maintained by contractile coil springs 65 affixed to the end rails 57 and 58 of the upper frame work, the said spring surface not being shown in the accompanying drawings in Figure 3. Numerals 66 and 67 represent orifices in the end rails of the upper frame work inwardly of the forward longitudinal rail 56 to be engaged by hooks 94 and 95 respectively mounted on the rear edges of end pieces 11 and 10 for a purpose hereinafter to be described. Numeral 62' represents a wire or band member extending from upright 60 to upright 59 and from upright 59 to upright 60' and serves as a cooperating support with the said uprights for the mattress 96 when the latter 20 is in vertical position.

The movable truck frame, as has been before mentioned, comprises an upper frame work and folding legs. Each pair of legs is preferably formed of a U-shaped bar as is shown in Figure 3. Thus legs 68, 68'' are the upright members of the bar and the lower connecting cross piece 68 the lower supporting means therefor. The upper ends of legs 68', 68'' are pivotally connected to the longitudinal rails 55 and 56 of the 25 upper frame work of the movable truck frame proximate the ends thereof as best seen by reference to Figure 7. The front rear leg 68' is pivoted at 72 to the inner wall of rail 55 at the top of the said leg 68'. Legs 68' and 68'' are 30 also reinforced by a V-shaped reinforcing member 69 affixed to the intermediate portion of cross-piece 68. Numeral 73 represents a projection, rounded preferably, on the outer surface of leg 68' a short distance from the top thereof, and 35 is adapted to engage with a suitable mortise or depression 74 on the inner wall of longitudinal rail 55. Numeral 75 represents an angle member riveted to end rail 55, and is adapted to serve as a limiting stop for the said leg 68' when in 40 outstretched or operative position as shown in Figures 5 and 7. Pivotally connected to the said leg 68' at pivot 77' approximately between projection 73 and pivot 72 is a link 77 connected to the front end rail 58 by contractile spring 78. It thus can be seen that leg 68' when in folded 45 position remains so by virtue of projection 73 in its mortise 74 and by virtue of the fact that pivot 72 is below pivot 77'. Leg 68'' is similarly provided with a projection and mortise therefor, an 50 angle member to serve as a limiting stop for leg 68'' and a pivotal link springably mounted from the front end rail 58.

Opposite legs 70' and 70'' are joined by a lower 55 connecting piece 70 and by a V-shaped reinforcing member 71. Leg 70' is provided with a projection 80 adapted to fit into a mortise 81, a limiting stop or angle member 82 for leg 70', a pivotal link 83 mounted to end rail 57 by a contractile spring 84. Leg 70'' is provided with 60 similar means.

From the foregoing, it is seen how the folding legs 68', 68'' and 70', 70'' remain in open position by the tension of the springable mounting thereof and the angle member stops and how the same legs remain in folded position by virtue of rounded projections and mortises therefor and by virtue of the off-center position of the legs with respect to their respective pivots. Very little hand pressure is required to open and close the legs of the movable truck frame.

End pieces 10 and 11 at the inner surfaces thereof and proximate to the rear edges are each provided with similar channel members 85 and 85' respectively. Each channel member is affixed to its respective end piece and comprises preferably a vertical slot open at the top and closed at the bottom, the said slot leading into a vertical chamber open at the top and closed at the bottom as best shown in Figure 6 of the accompanying drawings. Channel member 85 is thus provided 20 with a slot 85a and chamber 85b. Similarly, channel member 85' is provided with a slot 85'a and chamber 85'b.

End rails 57 and 58 of the truck frame proximate the forward edges thereof are provided 25 with outwardly projecting trunnions 87 and 86 respectively, the said trunnions being adapted to slide up and down of the slotted chambers of the channel members 85 and 85'. The said trunnions are provided with end disc members 87' and 30 86' respectively for engagement with the channel members 85 and 85'. It is thus seen how the movable truck frame is mounted on the end pieces 10 and 11 by merely raising the truck frame so that trunnions 87 and 86 together with their respective disc members 87' and 86' enter the 35 openings of the channel members 85 and 85'.

The rear edges of the end pieces 10 and 11 proximate the tops thereof are each provided with pivotal fingers adapted to hold the truck frame or 40 back of the convertible couch by engaging the end rails when the latter are in vertical position. Thus end piece 10 is provided with a finger 88 pivoted near the top of the rear edge thereof at pivot 89, the said finger 88 being provided with 45 a stop projection 90. Similarly, end piece 11 is provided with a finger 91 at pivot 92, the said finger 91 being also provided with a stop projection 93.

Orifices 66 and 67 in the end rails of the upper 50 frame work inwardly of the forward longitudinal rail 56 of the movable truck frame as has before been mentioned are engaged by hooks 94 and 95 respectively mounted on the rear edges of end pieces 11 and 10. These hooks and orifices are provided to insure against movement 55 of the rear portion of the convertible couch when the said rear portion is in the position of a single day bed adjoining the single day bed afforded by the stationary frame, and is in close proximity 60 thereto by virtue of the disconnection of trunnions 86 and 87 from channel members 85' and 85.

Figure 8 is a sectional view of an alternate manner of supporting the back member of the 65 convertible couch and differs from the described structure in that the channel members 85 and 85' are lengthened sufficiently to bring the rear longitudinal rail 55 of the movable truck frame or the rear of the convertible couch when in upright position below its prior position. By so 70 doing and by providing a supporting structure such as a plurality of brackets 97 to hold mattress 96 in vertical position above rail 55, a better looking top is given to the convertible couch. 75

At the same time uprights 60, 60', 59 and band members 62' are eliminated to support the back mattress 96 when in upright position. As shown, brackets 97 extend from rear wall 40 of the bedding storage compartment. It is easily seen that any other form of a support such as a ledge may be substituted for brackets 97 to function as a support for mattress 96 of the rear of the convertible couch when the said mattress is in upright position, the said support being suitably mounted from either the rear portion of the stationary frame or from the inner sides of the end pieces 10 and 11.

The convertible couch is susceptible of being upholstered in any known fashion, one form of upholstery being shown in Figure 1 of the accompanying drawings. Mattress 47 of the stationary frame and mattress 96 of the back or movable frame are fashioned to present the appearance of adjoining cushions.

The conversion of the couch to a double bed or to two single beds wherein the members are separable or are articulately joined at the option of the user involves a simple operation that a child can accomplish. Pairs of folding legs 68', 68" and 70', 70" are drawn outwardly into final open position by pulling the connecting pieces 68 and 70 respectively until the legs impinge against their respective stops through the action of the contractile springs already described. Thereupon fingers 88 and 91 are raised to upright position as shown in solid lines in Figure 5. Thus the rear support of the movable frame when in upright position is removed allowing the back or movable frame to pivotally drop outwardly by virtue of its own weight. Pivots 86 and 87 supporting and attached to the movable frame at this time rest on the bottom closed portion of slots 85'a and 85'a respectively and revolve thereabout. Pivots 86 and 87 are forced upwardly along the vertical slots 85'a and 85'a respectively from the time that legs 68" and 70" touch the ground until all the legs and the connecting cross pieces therewith touch the floor at once at which time the level of the truck frame is the same as the level of the single bed afforded by the stationary frame. Thus a double bed comprised of two single beds pivoted together results. By raising the pivots 86 and 87 out of the open tops of slots 85'a and 85'a respectively, the truck frame can be drawn more closely to the stationary frame and held in position by means of hooks 94 and 95 engaging with orifices 66 and 67 respectively. On the other hand, the truck frame instead of being drawn more closely to the stationary frame may be distantly removed therefrom and serve as an independent and single bed. Casters 98 ease the facility of movement of the truck frame.

Mattresses 47 and 96 are each removable from the springs of the stationary and the movable frames so that the same may be reversed and removed for the usual reasons. The ordinary expedients of keeping the said mattresses in place

such as tape members extending from the surfaces of the mattresses to be tied to the springs at suitable places can be resorted to. Such temporary affixation is especially necessary for mattress 96 since the latter is in upright position when the convertible couch is in non-bed use. Moreover, the spring surfaces themselves may be covered with cloth to protect the mattress thereagainst. The bedding compartment in the stationary frame serves to store the materials needed for the use of the convertible couch as a double bed or as two single beds.

In order to reassemble the stationary frame and the truck or movable frame into a convertible couch, pivots 86 and 87 are inserted into slots 85'a and 85'a respectively, the movable or truck frame is raised from the ground whereupon the weight of the said truck frame causes the pivots 86 and 87 to descend to the lowermost wall of slots 85'a and 85'a respectively. Thereupon the legs are folded inwardly. Fingers 86 and 91 are manually made to engage end rails 57 and 58 respectively of the truck frame to maintain the latter in upright position.

It is to be clearly understood that minor changes and variations in the structure of the several parts, in the material and integration thereof and in the combinations and subcombinations thereof may all be resorted to without departing from the spirit of the invention and without departing from the scope of the appended claim.

I claim:

In a convertible couch, a stationary frame having a bed spring surface, end pieces to support the said stationary frame, a second frame having another bed spring surface, foldable uprights connected to the said second frame and capable when extended of independently supporting the second frame horizontally at a height substantially the same as that of the first mentioned bed spring surface, pivotal securing means between the stationary and second frames comprising two elongated, vertically disposed channel members open at the top and closed on the bottom, each being oppositely affixed to the said end pieces rearwardly of and extending below the stationary frame, projections extending from the second frame and being mounted in the said channel members for rotation, removal and vertical displacement whereby the second frame when in upright position is spaced from the rear of the stationary frame and extends below the level of the stationary frame, supporting means projecting upwardly from the forward longitudinal edge of the second frame, duplicate loose mattresses supported on the said stationary and second frames, the said loose mattress against the second frame when the latter is in upright position being held in upright position by means of the above-mentioned supporting means and the rear longitudinal edge of the loose mattress for the stationary frame.

PHILIP CUTLER.
